UNITED STATES PATENT OFFICE

160,146

KNOCKDOWN MINIATURE OPENSIDED
PLAYHOUSE OR THE LIKEJoseph Brunetti, Carlstadt, N. J., assignor to
Columbia Protektosite Company, Inc., Carl-
stadt, N. J., a corporation of New Jersey

Application May 8, 1948, Serial No. 146,248

Term of patent 3½ years

(Cl. D34—15)

To all whom it may concern:

Be it known that I, Joseph Brunetti, a citizen of the United States and resident of Carlstadt, in the county of Bergen, State of New Jersey, have invented a new, original, and ornamental Design for a Knockdown Miniature Open-Sided Play House or the Like, of which the following is a specification, reference being had to the accompanying drawing, forming a part thereof, in which

Fig. 1 is a front elevational view of the knockdown miniature open-sided play house or the like, showing my new design;

Fig. 2 is a rear elevational view thereof;

Fig. 3 is a left side elevational view thereof;

Fig. 4 is a right side elevational view thereof; and

Fig. 5 is a top plan view thereof to a reduced scale.

Figs. 1, 3, and 4 are shaded to indicate transparency.

Portions visible through the open doors have been omitted for convenience of illustration.

I claim:

The ornamental design for a knockdown miniature opensided playhouse or the like, as shown and described.

JOSEPH BRUNETTI.
